Primary Examiner—Prabhakar Deshmukh

(74) Attorney, Agent, or Firm—Foley Hoag LLP

(57) **CLAIM**

The ornamental design for a gaming card, as shown and described.

DESCRIPTION

The sole FIGURE is the top plan view of the gaming card, showing the new design. The broken line number “3” in the top left hand corner of the figure is for illustrative purposes only, and forms no part of the claimed design.

1 Claim, 1 Drawing Sheet
